INVENTOR

Jules de Rose

UNITED STATES PATENT OFFICE.

JULES DE ROSE, OF SAN FRANCISCO, CALIFORNIA, ASSIGNOR TO MOSES COHN, OF NEW ORLEANS, LOUISIANA.

CORN-PLANER.

SPECIFICATION forming part of Letters Patent No. 413,712, dated October 29, 1889.

Application filed April 24, 1889. Serial No. 308,470. (No model.)

To all whom it may concern:

Be it known that I, JULES DE ROSE, a citizen of the United States, residing in the city and county of San Francisco, and State of California, have invented a new and useful 5 corn-planer for Planing Corns, of which the following is a specification, reference being had to the accompanying drawings and the letters referring thereto.

10 Figure 1 is a front elevation showing my improved corn-planer upon the toe in the position for operating upon the corn for removing the same. Fig. 2 is a perspective view of my corn-planer with the toe withdrawn. Fig. 15 3 is a perspective view showing the planer detached from the outside frame. Fig. 4 is a side elevation showing the corn-planer placed ready to operate upon a corn. Fig. 5 is a 20 broken sectional side elevation showing the machine cut vertically and longitudinally through the center, and Fig. 6 is a perspective view of the outside frame with the planer removed.

The following is the construction of my improved corn-planing machine: I form the 25 various parts of such metals and material as are commonly employed in that class of manufacture. I form the outer frame A with upright guides A', having the journal-bearing 30 slots K to fit inside of the guides C. To the outer frame A, I attach the adjustable toe-bearings H by means of set-screws I. The journal-hooks E are hinged so as to be swung off the journals when the planer is to be lifted 35 out to be used separately. I form the planer with a face-plate B, which is designed to have its bearing upon the top of the toe, and it has a throat D, similar to other planes, to allow the shavings or cuttings to be thrown out. It 40 also has the upright guides C, which secure it

in position laterally in the outside frame A, and the revolving plane-stock F, which carries the bit G, is attached to the same by means of the journal N, which is revolved by means of the crank J.

45 The following is the operation of my improved corn-planer: The outer frame A is placed upon the toe in such position that the corn required to be planed or cut is directly under the plane-stock F. Then the bearings 50 H are adjusted so as to hold firmly in position upon the toe, and as the stock F is revolved the bit G shaves off the corn, reducing it to a condition where it will cause no pressure, and consequently no pain. By repeated planings, 55 thereby removing the pressure, the corn soon disappears entirely from the toe. When the corn is upon a part of the foot not accessible because of the outer frame, I remove the planer from the outer frame A and hold it so 60 that the face-plate B will bear upon the foot and the corn be at the throat D. Then, the plane-stock and bit G being revolved, the corn is planed, as before described.

Having thus described my invention, what 65 I claim, and desire to secure by Letters Patent, is—

In corn-planing machines, the corn-planer composed of the frame B', with face-plate B, having the throat D, the revolving bit-stock 70 F, having the bit or cutter G, the journal N, and crank J, in combination with the outside frame A, having the journal-hooks E, the journal-slots K, the adjustable bearings H, and set-screws I.

JULES DE ROSE.
